UNITED STATES PATENT OFFICE.

HELGO WIGGO JESPERSEN, OF WESTERN SPRINGS, ILLINOIS, ASSIGNOR TO WESTERN ELECTRIC COMPANY, INCORPORATED, OF NEW YORK, N. Y., A CORPORATION OF NEW YORK.

MECHANISM FOR WORKING PULPOUS MATERIAL.

Application filed June 18, 1925, Serial No. 37,903. Renewed September 9, 1927.

This invention relates to improvements in mechanism for working pulpoous material, and more particularly to mechanism for forming such material to constitute a homogeneous coating for cores in strand form, such as wire and the like.

Mechanisms made in accordance with this invention are particularly well adapted for use in connection with the method of and apparatus for coating cores disclosed in Patent 1,615,423, issued January 25, 1927, to H. G. Walker, but it is to be understood that the invention is to be limited to such use only to the extent defined by the appended claims.

The apparatus disclosed in the application above referred to is adapted to attach a ribbon of pulp to a core in such manner that the pulp may be subsequently formed into a coating for the core, which coating substantially conforms to the shape of the core. When the attached pulpoous ribbon is substantially uniform throughout its length, a substantially uniform homogeneous coating may be formed on the core. However, irregularities sometimes occur in the pulpoous ribbon due to abnormal increases in the thickness of the attached pulp, which irregularities have in some instances heretofore rendered the formation of a satisfactory coating very difficult.

The primary object of this invention is to provide an improved mechanism for forming pulpoous material on a core, which is so designed that a satisfactory product may be produced regardless of any irregularities in the distribution of the attached pulpoous material.

In order to obtain this object in accordance with the general features of one embodiment of the invention, there is provided a rotatable head which is adapted to carry a plurality of forming members disposed to engage the pulpoous material on a core being drawn through the head. One of the forming members is pivotally mounted intermediate its ends and is provided with pulp engaging portions on both sides of the pivot point, either one or both of which constantly engage the moving core and its attached pulp. The pulp engaging portion in front of the pivot point is so designed as to preliminarily wrap the pulpoous material around itself and the core before it is sub-

jected to the wrapping operation of the portion to the rear of the pivot point and a cooperating relatively fixed forming member. The heavier front engaging portion, due to the pressure positively exerted thereon by the pulpoous material and the action of centrifugal force thereon, causes the immediate restoration to its normal operating position of the rear engaging portion, which portion may have become displaced due to the passage between it and the cooperating relatively fixed forming member, of a section of core having an abnormally thick pulp coating. Both forming members are mounted on eccentric pivots to permit their individual adjustment relative to each other and to the core.

Other features and advantages of the invention will become apparent in the following detailed description, reference being had to the accompanying drawings, wherein

Fig. 1 is a side elevation of a forming mechanism embodying the features of the invention;

Fig. 2 is a longitudinal section taken on the line 2—2 of Fig. 1;

Fig. 3 is an end view of the mechanism shown in Figs. 1 and 2, partly in section, taken on the line 3—3 of Fig. 2;

Figs. 4 and 5 are enlarged sectional views illustrating the manner in which the pulp is applied to the core before it is delivered to the forming mechanism, and

Figs. 6 and 7 are enlarged sectional views showing the forming of the pulp coating during the forming operation, and after the completion of the forming operation, respectively.

The forming mechanism herein shown and described is especially adapted to be used in conjunction with the apparatus shown and described in the aforementioned patent application, which apparatus is adapted to apply pulpoous material to a core. In the operation of this apparatus the core is first brought into contact with pulpoous material deposited upon a foraminous member and then an additional amount of pulpoous material is deposited upon the core and the foraminous member. The pulp so deposited and the core are then brought into contact with one of a pair of felt covered squeezing rolls which cooperates with the foraminous member to squeeze out the "free

liquid" in the pulp mixture. The partially dried pulp adheres to the felt of the squeezing roll in the form of a ribbon with the core substantially centrally located therein, as is shown in Fig. 4 of the accompanying drawing. The core with the pulp ribbon attached thereto is then passed through the squeezing rolls which impart to the pulpyous ribbon a contour such as illustrated in 10 Fig. 5.

A forming mechanism embodying the features of the present invention is designed to receive a core and its pulpyous ribbon from the squeezing rolls and wrap the projecting 15 edges of the ribbon around the core and around each other until the contour of the coating conforms substantially to the shape of the core. The appearance of the coating after it is first acted upon by the forming 20 mechanism is shown in Fig. 6, and its appearance after the forming operation is completed is shown in Fig. 7.

Referring now to the drawing in detail, 10 indicates, generally, a rotatable head or 25 carrier of substantially tubular construction and having one of its ends threaded into a sleeve 12 (Fig. 2), which sleeve is rotatably journaled in a plurality of bearings, one of which is shown at 13. The sleeve 12 may 30 be rotated by any suitable means (not shown) and thus constitutes means for rotating the head 10. The head 10 and sleeve 12 are provided with central longitudinal apertures 14 and 15, respectively, whereby 35 they are adapted to accommodate a core 16 with its pulpyous ribbon 17 drawn through them by any suitable means (not shown).

Pivoted in bifurcations 19 and 20 of the head 10 are a pair of forming 40 members 21 and 22 which are disposed in opposed relation and are adapted to receive the core 16 and its pulpyous ribbon 17 between them. The core 16 is drawn through 45 the forming mechanism in the direction indicated by the arrow 25 in Fig. 2. Those ends of the forming members 21 and 22 which first receive the core as it is drawn into the forming mechanism are turned outwardly as indicated at 26 and 27, respectively, 50 so that the pulp ribbon is gradually wrapped around itself and the core as it enters the forming mechanism.

The forming member 22 is pivoted intermediate its ends, and a portion 28 thereof 55 extending to one side of the pivot projects forwardly beyond the head 10 and the end 26 of the forming member 21 and constantly engages the ribbon of pulp as it approaches the forming mechanism, thereby serving to 60 preliminarily wrap it around itself and the core before it is subjected to the cooperating wrapping operation of both forming members. The formation of pulpyous ribbon 65 around the core after it has been acted upon by the forwardly projecting portion 28 of

the forming member 22 is substantially as shown in Fig. 6.

Means is provided for adjusting the forming members towards and away from each other to accommodate cores of various diameters or to vary the thickness and density of the pulpyous coating. Formed at one end of the member 21 is an ear 30 whereby the member is pivotally mounted on an eccentric 31, and formed integral with the member 22, intermediate its ends, is an ear 33 whereby such member is likewise pivotally mounted on an eccentric 34. The eccentrics 31 and 34 are rotatably mounted on pins 35 and 36, which pins are rigidly journaled in 80 the bifurcations 19 and 20, respectively, (Figs. 2 and 3). Knurled thumb nuts 37 and 38 formed at the ends of the eccentrics 31 and 34, respectively, facilitate the turning of the eccentrics to adjust the forming 85 members towards or away from each other.

When the head 10 is rotated centrifugal force causes the inner portion 39 of the forming member 21 to move outwardly, which outward movement may be adjusted 90 to accommodate a core of any predetermined diameter by means of a set screw 40 threaded through the head 10 and engaging the outer surface of the member 21 (Fig. 2). Also, since the portion 28 of the forming member 95 22 which projects forwardly from the pivot 34 is heavier than the rearwardly projecting portion 41 thereof, it is obvious that centrifugal force will cause the portion 41 to move inwardly causing the core 16 and its pulpyous ribbon 17 to be pressed thereby against 100 the inner surface of the member 21.

The forming members 21 and 22 are preferably composed of resilient sheet metal. It is obvious therefore that during the rotation of the forming mechanism centrifugal force causes the forwardly projecting portion 28 of the forming member 22 to move outwardly to a slight degree, thereby assuming a position substantially as indicated by the dotted lines in Fig. 2.

Referring to Fig. 2, it will be noted that the forming members 21 and 22 are so arranged with respect to the bifurcated end of the head that they may be quickly and easily cleaned whenever it becomes necessary to do so. A cloth or brush may be drawn back and forth through the slotted end of the head and between the forming members in such manner that any pulpyous material adhering to the surfaces thereof may be readily disengaged therefrom.

In the operation of the above described forming mechanism the core 16, together with its pulpyous ribbon 17 is drawn through the head 10 and the sleeve 12, the head and sleeve being rotated at a speed which causes the portion 28 of the forming member 22 to generate a centrifugal force sufficient to bring the portion 41 thereof into pressing 125 130

engagement with and exert the desired pressure upon the pulpos material on the core. The pulpos ribbon is first engaged by the forwardly projecting portion 28 of the forming member 22 which is designed to preliminarily form the pulp around the core as illustrated in Fig. 6. As the pulp covered core passes between the portions 39 and 41 of the forming members 21 and 22, respectively, the pulpos material is formed into a smooth homogeneous coating which conforms to the shape of the core, as illustrated in Fig. 7. The thickness and density of the coating is determined by the amount of pulp that is attached to the core and also by the pressure exerted thereon by the pulp engaging portions 39 and 41 of the members 21 and 22, respectively, which pressure may be varied by changing the rotating speed of the forming mechanism. The distance between the pulp engaging portions of the forming members may be varied by means of the adjustable eccentrics which render the forming mechanism readily adaptable 25 to accommodate cores of various diameters.

As hereinbefore described, the arrangement of the forming members is such that an irregularity, such as a lump or other abnormal thickness of the pulpos material, is first engaged by the forwardly projecting portion 28 of the forming member 22 as the core enters the forming mechanism. It is apparent that upon encountering any such irregularity the forwardly projecting portion 28 moves outwardly away from the core, thereby turning the member 22 on its pivot 34 in a clockwise direction and causing the inner portion 41 thereof to move towards the core. While passing between the inner portions 39 and 41 of the members 21 and 22, respectively, the irregularity causes the portion 41 of the member 22 to move outwardly, away from the core, thereby moving the forwardly projecting portion 28 thereof towards the core. However, as soon as the irregularity passes the inner ends of the member 22, such member 22 will immediately resume its normal position due to the centrifugal force generated by the outwardly projecting portion 28 materially assisted by the increased pressure which is positively applied thereto by the engaged pulpos material.

By using a forming mechanism embodying this invention a satisfactory product may be obtained even through the pulpos material is applied to the core non-uniformly. This is accomplished by the cooperating forming actions of the portions 28 and 41 of forming member 22. Upon an irregularity, such as that due to an abnormal increase in the thickness of the applied pulp, engaging the rearward portion of the forming member, it opposes the pressure applied thereto due to the action of centrifugal force

upon the heavier forward portion and causes the latter portion to exert a greater pressure on the pulpos material. However, as soon as the abnormal section of coating passes beyond the rear end of the forming member, such member is immediately restored to its normal operating position, wherein it produces a satisfactory product. This restoration is brought about by the action of centrifugal force upon the forward end of the member, aided materially by the pressure positively exerted thereon by the pulpos material engaged thereby. In this way, although the rearward portion of the forming member is displaced from its operative position by the irregularity, the forward portion approaches the core and wraps the pulpos material more closely than under normal conditions, so that the portion of the coated core so wrapped requires a lesser amount of forming to be done by the rear portion of the member.

From the above description it is apparent that the improved forming mechanism is very simple and economical in construction, readily cleaned and adjustable, and efficient in its operation, all of which renders the mechanism very suitable for the use intended.

What is claimed is:

1. In a mechanism for working pulpos material on a core, a forming member movable in an arc about a pivot disposed intermediate its ends and having pulp engaging portions extending on either side of the pivot point.

2. In a mechanism for working pulpos material on a core, a forming member movable in an arc about a pivot disposed intermediate its ends and having pulp engaging portions extending on either side of the pivot, one of said pulp engaging portions being so shaped that it preliminarily wraps the pulpos material around the core before it is subjected to the forming operation of the other pulp engaging portion.

3. In a mechanism for working pulpos material on a core, a forming member having a pulp engaging portion pivotally mounted on an eccentric whereby it may be spaced at a predetermined distance from the core.

4. In a mechanism for working pulpos material on a core, a forming member movable in an arc about a pivot disposed intermediate its ends and having pulp engaging portions extending on either side of the pivot point, and means for adjusting said forming member toward and away from the core.

5. In a mechanism for working pulpos material on a core, a pair of oppositely disposed forming members, one of said forming members having a pulp engaging portion projecting in front of the other forming

member and so designed that it preliminarily wraps the pulpos material around itself and the core before it is subjected to the forming operation of the other forming member.

6. In a mechanism for working pulpos material on a core, a pair of oppositely disposed forming members, one of said forming members having a pulp engaging portion projecting in front of the other forming member so designed that it preliminarily wraps the pulpos material around itself and the core before it is subjected to the wrapping operation of the other forming member, and means for spacing the forming members at a predetermined distance from the core.
7. In a mechanism for working pulpos material on a core, a rotatable member carrying a pair of oppositely disposed cooperating forming members pivotally and adjustably mounted on eccentrics, one of said forming members having a pulp engaging portion projecting in front of the opposite forming member, said portion being so de-

signed that it preliminarily wraps the pulpos material around itself and the core before it is subjected to the cooperating forming operation of both forming members.

8. In a mechanism for working pulpos material on a core, a rotatable member having a bifurcated portion, a pair of oppositely disposed forming members pivotally mounted upon eccentrics within said bifurcated portion, one of said forming members having pulp engaging portions extending on either side of the pivot, one of which projects forwardly beyond the forward end of the opposite forming member and is so designed that it preliminarily wraps the pulpos material around the core, and the other pulp engaging portion being so designed that it cooperates with the oppositely disposed forming member to subsequently form the pulpos material into a homogeneous 40 45 coating for the core.

In witness whereof, I hereunto subscribe my name this 5 day of June A. D., 1925.

HELGO WIGGO JESPERSEN.
